COMBINATION RECEIVER AND REGENERATOR UNIT FOR REFRIGERATING PLANTS

Norman H. Gay, Los Angeles, Calif.

Application January 6, 1932. Serial No. 585,081

17 Claims. (Cl. 62—115)

This invention relates to improvements in refrigerating plants, and more particularly concerns an assembly whereby certain parts of such plants, customarily manufactured separately and connected by piping and valves, may be combined into units whereby the amount of piping and the number of valves is reduced.

One of the features of the present invention is the provision of a refrigerating plant adapted for automatic and semi-automatic operation, and comprised of a single unit for receiving the liquid refrigerant with means for recovering or regenerating refrigerant medium from trapped oil and foreign gas, and means for controlling the flow of liquid refrigerant from the high pressure or condensing portion of the plant to the low pressure or evaporating portion thereof.

Another feature of the present invention is the provision of a unit for a refrigerating system comprising a receiver and a regenerator, combined in a single structure.

A further feature of the present invention is the provision of a receiver including a control float and valve, and a regenerator, with other associated parts, the receiver and regenerator being assembled as an integral piece.

With these and other objects in view as will appear in the course of the following specification and claims, an illustrative embodiment of the invention is set forth on the accompanying drawings, in which:—

Figure 1 is a diagrammatic view showing the relationship of the parts of a refrigerating system including the present invention.

Figure 2 is a top plan view, on a larger scale, of the receiver and regenerator unit.

Figure 3 is a side elevation of the same.

Figure 4 is a sectional view substantially on line 4—4 of Figure 3.

Figures 5 to 8 show a modified form of receiver.

Figure 8 shows a further modification in the receiver.

In these drawings, the compressor 10 receives gaseous refrigerant and pumps it, under increased pressure, through a pipe line 11 and an oil trap 12, past a shut-off valve 13 into a condenser 14 where the refrigerant is condensed to a liquid and flows through an outlet pipe 15 and shut-off valve 16 into the receiver. With some types of condensers,

e. g. some shell condensers where the lighter non-condensable gases accumulate in the condenser, such non-condensable gases may enter an outlet or purging pipe 17 and pass a shut-off valve 18.

It will be understood that such gases of non-condensable nature commonly referred to as foul

or foreign gases, are usually present because of impurities in the refrigerant employed, and because of leakages from the atmosphere into the system. These gases may be heavier or lighter than the refrigerant gas itself. In some types of condensers, both the heavier and lighter non-condensed gases pass along with the condensed refrigerant in pipe 15 to the receiver 19. With other types, as referred to above, only the heavier non-condensed gases pass forward through the pipe 15. In any event, the ultimate result in the present system is to bring the non-condensed gases into a regenerating coil as will be described hereinafter.

The liquid leaving the receiver-chamber 19 is controlled by a float 20 with an associated valve 44. This valve 44 is illustrated conventionally as comprising a disc having a perforation there-through which, according to the position of float 20, is in registry or out of registry with a corresponding aperture in the valve body, and thus permits or shuts off communication between the interior of the receiver 19, through pipe 44a, with the liquid refrigerant line 21, which has a shut-off valve 22 for controlling communication with the evaporator 23.

The liquid refrigerant evaporates in the evaporator 23 in known manner and thus reduces the temperature of the medium surrounding the evaporator, and the resulting gaseous refrigerant finally escapes through a pipe 24 and shut-off valve 25 back to the compressor, for a return in cycle. Any non-evaporable liquid, such as oil, water, etc., in the evaporator is drawn off into a trap 26 from which it may pass through a shut-off valve 27 into a common liquid purging line 28.

The oil from the gaseous refrigerant trap 12 is likewise passed through a shut-off valve 29 to a pipe line 30 and thus into the common liquid purging line 28. The pipe 28 passes the oil or other liquid contained therein through a valve 31 into the upper regenerator casing or chamber 32 of the receiver-regenerator unit. It will be understood that if it be desired to operate independently of the float valve, as for example, if the valve 44 become obstructed for any reason, the valve 20a may be opened to a desired degree so that the liquid may flow from the receiver-chamber 19 through pipe 21a into pipe 21.

A gaseous refrigerant pipe 33 having a shut-off valve 34 leads from the top of the regenerator housing 32 and communicates with pipe 24 and thus with the compressor 10.

As shown in Figures 2, 3 and 4, the lower or receiver housing 19 has the closing bottom wall

40 and the top wall 41. The pipe 15 enters it between these walls, and a baffle 42 is provided which terminates short of the top and bottom of the same to direct the entering refrigerant liquid downwardly and gas upwardly within the receiver, so that the liquid refrigerant establishes a pool in the receiver, while gaseous refrigerant as well as non-condensable gas may collect in the upper portion thereof. The float 20 is mounted 10 on a float rod 43 which communicates with a valve structure 44 carried by a flange 45 which is bolted to an offset 46 on the wall of the receiver. Any oil or other heavier non-evaporable liquid in the refrigerant liquid may settle out in this receiver and collect in the bottom thereof, from 15 which it may be drawn off from time to time through a pipe line 47 which passes through the upper wall 41 and enters the housing 32 of the regenerator unit near its top, being provided with a shut-off valve 48. The upper housing 32, 20 containing the regenerator parts, is fixed to the top wall 41 of the receiver, by welding, and is closed at the top by a wall 49. The pipe 33 passes centrally through the top wall 49 and thus establishes communication with the interior of housing 32. The gas purging pipe 17 likewise passes through this top wall, and establishes communication with the interior of coil 50.

Located within the regenerator unit is a coil 50 having its lower end 51 passed through the top wall 41 of the receiver and thus establishing communication with the interior of the receiver. The upper end 52 of this coil extends through the wall of housing 32 and connects with a short pipe 53 having a shut-off valve 54 leading to a nipple 55 to which may be connected a hose 56 leading into a container 57 of some chemical, usually water for absorbing any traces of refrigerant gas passing out with the non-condensable gas. This 35 container 57 is mounted on a shelf 58 supported by a bracket 59 secured to the housing 32. The purging gas pipe 17 passes downward within the regenerator and is connected to the coil 50 at an intermediate point of the height thereof, so that 40 purged gas is brought into this coil at a point between the top and bottom thereof.

A draw-off pipe 60 passes through the housing 32 and opens into the regenerator near the bottom thereof, closely adjacent the top wall 41 of the receiver, and is provided with a shut-off valve 61 and a discharge pipe 62 which (Figure 1) is illustrated as leading to a bucket 63.

The nipples 70 may be provided in the receiver housing and connected by valves 71 with a gauge glass 72 which permits reading the height of refrigerant within the receiver. During operation of the plant in its cycle, oil and other non-evaporable liquid is separated in the traps 12 and 26, and in the receiver 19, while non-condensable gas is conducted from the condenser into coil 50, either directly through the purging pipe 17 for light non-condensable gas as set forth above, or by passage into the receiver 19 along with the liquid and thence upwardly into the coil end 60 51. During the course of the circulation in cycle, the attendant may open valve 27 from time to time to relieve the accumulated liquid from trap 26 into pipe 28; and alternating therewith the valve 29 may be open to cause the relief of liquid 65 from the trap 12 into the pipe 28. During this latter operation, the pressure existing in the compressor and condenser causes the forcing of all liquid in pipe 28 into the upper or regenerator chamber 32. Normally the valve 29 is left partly 70 open until the heat of gases passing valve 29

causes a warming of the branch pipe 30, whereupon the valve 29 is closed again. In this way the liquid is forced from pipe 28 through valve 31 into the regenerator chamber 32. As is well known, a considerable quantity of the refrigerant 80 used is normally dissolved in the oil and other liquid separated in the trap 26 and in the receiver 19, and usually also in the liquid separated at 12. The liquid from the traps, along with such gas as may develop there due to drop in pressure in line 28, causing entrained refrigerant liquid to expand, passes onward through valve 85 31 into regenerator body 32, where the process of regeneration causes the refrigerant to evaporate and pass out through line 33 and back to the compressor, while the remaining non-evaporable liquids are drawn off through line 60 and valve 61 into a receptacle 63 and disposed of.

The purged or foul gas passing through pipe 17 or to the receiver 19 through pipe 15 enters the coil 50 at the bottom or a part of the height thereof. This coil, however, is being constantly chilled by the evaporation of the refrigerant contained in the entering oily liquid which surrounds the coil. Refrigerant gas accompanying 100 the non-condensable gas coming in contact with the interior of this chilled coil is condensed to a liquid. Hence, the foul gas is continuously being deprived of its refrigerant gas content, the condensed liquid from this latter gas passing out 105 through the end 51 of the coil and entering the receiver. Non-condensable gas from the receiver or from line 17 may pass continuously upward in the coil and thus be brought to the extreme upper end of this coil. It will be noted that by introducing the purged gas into the coil, a storage 110 chamber is provided in which the foul gas is substantially quiescent and hence may be freed of its admixed refrigerant gas. From time to time the valve 54 may be opened and the foul gas 115 blown off at which time any traces of refrigerant gas remaining may be absorbed in the vessel 57.

Further, it will be noted that any oil separating in the receiver portion of the unit will be blown off upon opening the valve 48 by the pressure 120 differences existing in the receiver and regenerator, and this ascends in pipe 47 and enters the top of the regenerator unit.

In the form of execution shown on the drawing, the float valve is limited in its upward movement by the engagement of the float rod 43 with the inner wall of the projection 46.

In disassembling the refrigerating system for repair, the various shut-off valves may be closed. Thus it is possible to separate the complete regenerator-receiver unit by closing the valves 18, 130 34, 31, 16 and 22, and disconnecting the pipes which connect these valves with the unit, e. g. by separating the flanges of valves 18. Usually, the receiver 19 is completely drained by opening valve 135 48, and closing the inlet valve 16, so that substantially all refrigerant is withdrawn from the receiver itself. Prior to this operation, as is usual, the valves 18 and 16 are closed and the compressor operated so that all refrigerant medium 140 is passed into the portion of the system external to the regenerator and receiver units. By combining the receiver and regenerator into a single structure, the number of shut-off valves required is greatly reduced, and therewith the possibilities of leakage through such valves.

In Figures 5 to 8 are shown slight modifications which can be incorporated into the structure already described with certain advantageous effects as will be pointed out hereinafter.

In Figure 5 the housing 19a has the bottom wall 40a and top wall 41a, together with the liquid inlet conduit 15, the gas outlet conduit 51, the projecting tubular piece 46a having the closing wall 45 in which is received the liquid refrigerant outlet line 44a from the float valve 44 to the conduit 21. In this construction, however, the tubular member 46a does not terminate at or adjacent the receiver wall, but extends across the receiver chamber, substantially the upper half of it being cut away along the lines 46s. The extreme end may be joined by a welding seam 46v to the opposite wall of the receiver 19a, while a bottom aperture 46p is provided therein between this wall and the baffle 42x, which latter in the present instance extends from an upper end at which it obstructs the free fall of liquid from the liquid line 15, down to the bottom of the extended portion of the tubular member 46a, to which it may be welded. Extending upwardly from the lines 46s (Figure 7), at which the tubular member 46a was cut and joined for example by welding to this member, are the baffle walls 42s which extend chordally (Figure 6) across the receiver chamber and rise to a point above the maximum liquid level which is indicated by the dot-and-dash lines "Max" in Figure 5. The baffle 42x is joined to these walls so that a very rigid baffle structure exists within the chamber and around the float 20.

With this construction, the liquid entering from the liquid line 15 comes against the baffle 42x, and the gas therein may pass upward over the baffle walls 42s, 42x and into the upper part of the chamber, while the liquid moves freely downward inside of these baffle walls and through the aperture 46p to the bottom of the receiver chamber. As the liquid level rises in the receiver chamber, it finally overflows the baffles and passes into the float trough formed by the walls 46a, 42s, and thus raises the float 20 and moves the float valve 44 in the manner described above. In this way, less turbulence exists within the portion of the receiver chamber external to the float trough, and hence a better segregation of the non-evaporable liquid may be accomplished by gravity, this liquid settling into the bottom of the chamber so that it may be withdrawn through the pipe conduit 47. Hence, the structure leads to a greater efficiency in the separation of the non-evaporable liquid, and hence in the efficiency of the combined units.

In the form shown in Figure 8, the receiver 19b is likewise provided with the tubular member 46b, which extends into the chamber and is cut away at lines 46s so that again a float trough is provided for the float 20. This trough, however, is illustrated in Figure 8 as having a welded end plate 46k which is spaced from the adjacent wall 60 of the chamber, while the vertical baffle partition 42y is substantially identical with the baffle 42 of Figure 4, and preferably is secured to and stiffened by the end plate 46k, as by a weld seam 42ya.

In general, the operation of the device of Figure 8 is the same as that of Figure 5, except that the liquid in the receiver chamber does not rise to above the maximum level before it enters the trough.

It is obvious that the invention may be modified in many ways within the scope of the appended claims.

Having thus described the invention, what I claim as new and desire to secure by Letters Patent, is:—

1. In a refrigerating system including a compressor, a condenser, a receiver and an evaporator and pipes for connecting the same, a gas purging line connected to said condenser, the combination of a unit including said receiver and a regenerator, a coil within said regenerator in communication with the upper portion of said receiver, a connection between said purging line and said coil, means for introducing liquid refrigerant into said regenerator and means for withdrawing gaseous refrigerant therefrom, and a non-condensable gas discharge line connected to the upper end of said coil and including a discharge valve. 80

2. A refrigerating system as in claim 1, in which a trap is provided in said system between the condenser and the evaporator for separating non-evaporable liquid from the refrigerant liquid, and said introducing means establishes communication between said trap and said regenerator for introducing mixed non-evaporable and refrigerant liquid into said regenerator. 85

3. A refrigerating system as in claim 1, in which said gas purging line communicates with said coil at a point intermediate the height of 100 said coil. 100

4. A refrigerating system as in claim 1, in which a non-evaporable liquid discharge line establishes communication between the bottom of said receiver and the top of said regenerator, 105 and a valve is located in said liquid discharge line for closing the same. 105

5. In a refrigerating system including a compressor, a condenser, a receiver, an evaporator and conduits for connecting the same, the combination of a unit including said receiver and a regenerator, a coil within said regenerator in communication with the upper portion of said receiver, a float in said receiver, a valve located in the conduit between the receiver and the evaporator and operated by said float, means for withdrawing gaseous refrigerant from said regenerator, and a non-condensable gas discharge line connected to the upper end of said coil. 110

6. A receiver structure for a refrigerating system comprising a housing, a vertical partition in said housing spaced from the top and bottom thereof, a refrigerant liquid inlet line communicating with said receiver at one side of said partition whereby gaseous refrigerant may pass over the top of said partition and liquid refrigerant under the bottom of said partition, a float within the receiver housing at the opposite side of said partition, a conduit and a valve therein for the outlet of liquid from said housing, a swinging float arm for connecting said float and valve, and means rigid with the receiver housing for limiting the movement of said float arm. 120

7. A unitary receiver-regenerator structure for a refrigerating system, comprising walls providing two separate chambers at different levels, a coil within the upper chamber and itself communicating with said lower chamber for providing an upward passage for refrigerating gas contaminated with non-condensable gas into said coil and downward drainage for refrigerant liquid out of said coil into said lower chamber, a non-condensable gas discharge line leading from the upper end of said coil, a refrigerant gas suction line communicating with said upper chamber, means for introducing refrigerant liquid into said upper chamber, and means for introducing refrigerant and non-condensable gas into 130

said lower chamber. 135

8. A unitary receiver-regenerator structure as in claim 7 for a refrigerator system which includes a trap for separating non-evaporable liquid from refrigerant liquid, in which said liquid introducing means is connected with said trap for introducing mixed non-evaporable and refrigerant liquid into said upper chamber and outside said coil.
9. A unitary receiver-regenerator structure as in claim 7 for a refrigerator system which includes a trap for separating non-evaporable liquid from refrigerant liquid, in which said liquid introducing means is connected with said trap for introducing mixed non-evaporable and refrigerant liquid into said upper chamber and outside said coil, and including means connected with the bottom of said upper chamber for withdrawing non-evaporable liquid therefrom.
10. In a refrigerating system having a compressor, a condenser, a receiver, and evaporator and conduits for connecting the same in circuit, the combination of a regenerator housing, a coil within said housing and communicating with said receiver and providing upward passage of refrigerating gas contaminated with non-condensable gas from said receiver into said coil and downward drainage for refrigerant liquid from said coil into said receiver, a non-condensable gas discharge line leading from the upper end of said coil, a refrigerant gas suction line for establishing communication between said housing and said compressor, means for introducing a mixture of refrigerant liquid and non-evaporable liquid into said housing, and means whereby non-evaporable liquid may be withdrawn from said housing.
11. A system as in claim 10 including a purged gas line from said condenser for establishing communication with said coil at an intermediate point of the height thereof.
12. In a refrigerating system having a compressor, a condenser, a receiver, an evaporator, and conduits for connecting the same in circuit, a non-evaporable liquid trap located between said compressor and condenser, a non-evaporable liquid trap located at the outlet of said evaporator, a regenerator housing, conduits including valves for connecting said traps with said regenerator housing, a conduit for connecting said housing with the compressor so that said housing may be evacuated, a purged gas cooling means located within said regenerator, and a connection from
- 55
- 60
- 65
- 70
- 75
- said cooling means for providing pressure induced gas flow from and gravitational flow of refrigerant liquid into said receiver.
13. A refrigerating system as in claim 12, including a non-evaporable liquid discharge line from the bottom of said receiver into said regenerator, and a valve for closing said line.
14. A refrigerating system having a compressor, a condenser, a receiver, an evaporator, and conduits for connecting the same in circuit, a non-evaporable liquid trap located between said compressor and condenser, a non-evaporable liquid trap located at the outlet of said evaporator, a regenerator housing, lines including valves for connecting said traps with said regenerator housing, a line for connecting said housing with the compressor so that said housing may be evacuated, a purged gas cooling means located within said housing, and a valved connection from said receiver into said regenerator housing so that pressure in said receiver will force liquid therefrom into said regenerator housing, whereby the evacuation of said regenerator housing will produce a refrigeration of said purged gas cooling means.
15. A refrigerating system as in claim 14 including a valve in the conduit from the receiver to the evaporator, and a float in said receiver for operating said valve.
16. A receiver-regenerator structure for a refrigerating system comprising walls for providing a closed receiver, means for admitting refrigerant liquid and non-condensable gas into said receiver, means for withdrawing refrigerant liquid from said receiver, a heat-exchange regenerator comprising a heat-absorbing portion and a heat-yielding portion, means for passing mixed refrigerant and non-condensable gases from said receiver into said heat-yielding portion, means for admitting mixed refrigerant liquid and non-evaporable liquid into said heat-absorbing portion, and a suction conduit for evacuating said heat-absorbing portion.
17. A receiver-regenerator structure as in claim 16, in which said liquid admitting means includes a conduit in communication with said receiver near its bottom whereby mixed non-evaporable liquid and refrigerant liquid may flow from said receiver into said heat-absorbing portion.
